REFRIGERATION

Edmund A. Fenander, Yonkers, N. Y., assignor
to Servel, Inc., New York, N. Y., a corporation
of Delaware

Application March 4, 1938, Serial No. 193,843

3 Claims. (Cl. 62—2)

My invention relates to refrigeration, and has for its object to provide an improved system for transferring heat so that cooling may be effectively produced at a place above a source of refrigeration.

The above and other objects and advantages of the invention will be better understood from the following description and accompanying drawing forming a part of this specification, and of which the single figure more or less diagrammatically illustrates a heat transfer system embodying the invention.

Referring to the drawing, the invention is shown in connection with a cooling element or evaporator 10 of a refrigeration system of a uniform pressure type and like that described in application Serial No. 107,852 of Albert R. Thomas, filed October 27, 1936, and which has matured into Patent No. 2,207,838. It should be understood, however, that the invention is not limited to the specific refrigeration system described in the aforementioned Thomas application. For purposes of description, however, it may be considered that the disclosure of the aforementioned application is incorporated in this application.

The cooling element or evaporator 10 shown in the drawing constitutes a source of refrigeration and comprises an outer shell 11 which is embedded in insulation 12. Liquid refrigerant, such as ammonia, enters the upper part of the cooling element through a conduit 14. An inert gas, such as hydrogen, enters the upper part of the cooling element from the upper end of a cylinder 15 disposed within the shell 11. Liquid refrigerant evaporates and diffuses into inert gas within the cooling element to produce a refrigerating effect. This refrigerating effect is utilized to cool and liquefy a volatile fluid flowing through a coil 16 which is arranged about cylinder 15 and over which the liquid refrigerant flows.

The operation of the entire refrigeration system with which cooling element 10 is associated is set forth at length in the aforementioned Thomas application and will be here briefly described. If desired, reference may be had to the aforementioned application for a more detailed description of operation.

Briefly, the resulting gas mixture of refrigerant and inert gas flows from cooling element 10 through a conduit 17 to an absorber in which the refrigerant is absorbed into a liquid absorbent, such as water. The inert gas is returned to

cylinder 15 through conduit 18 and the enriched absorption liquid is conducted to a generator. By heating the generator the refrigerant is expelled from the absorption solution, liquefied in a condenser, and then returned to cooling element 10 through conduit 14 to complete the refrigerating cycle. The weakened absorption liquid from which refrigerant has been expelled is conducted from the generator to the absorber to absorb refrigerant vapor. In order to simplify the drawing, the absorber, generator, and condenser of the refrigeration system have not been shown, their illustration not being necessary for an understanding of this invention.

15 The coil 16, which is arranged within and in thermal relation with cooling element 10 of the refrigeration system just described, forms the condenser of a heat transfer system for producing cold at a place above the cooling element 10. The coil or condenser 16 is disposed below an evaporator 19 which is of the flooded type and located in a thermally insulated storage space 20. The evaporator 19 includes a receiver 21 and a looped coil 22 having a plurality of heat transfer fins 23 for increasing the heat transfer surface.

20 The condenser 16 and evaporator 19 form part of a closed fluid circuit which is partly filled with a suitable volatile liquid such as methyl chloride, for example, that evaporates in evaporator 19 and takes up heat thereby producing cold. The vapor flows from evaporator 19 through a conduit 24 into condenser 16 and the vapor is cooled and condensed by cooling element 10. The condensate formed in condenser 16 flows through a conduit 25 into a vessel 26.

25 In accordance with this invention liquid condensate is returned to evaporator 19 by a liquid transfer device 27. The device 27 includes a casing 28 into which liquid flows from vessel 26 through a conduit 29. Liquid is raised from casing 28 through conduit 30 to the upper part of receiver 21 of the evaporator. A check valve 31 is provided in the lower part of conduit 30.

30 Within casing 28 are disposed two solenoid coils 32 and 33 separated by a non-magnetic spacing block 34. The coils 32 and 33 are hermetically sealed within the casing by a non-magnetic hollow cylinder 35 which is welded or brazed to an annular non-magnetic member 36. The member 36 is secured at its outer periphery to the inside of casing 28. The lower end of cylinder 35 is closed and fits into an opening in a lower end-plate 37. The end-plate is secured to the closed end of cylinder 35 and the lower end of the cas-

ing, as by welding or brazing, for example. With this arrangement the coils 32 and 33 are effectively sealed and out of contact with liquid which flows into the casing through conduit 29.

A piston 38 is movable within the upper part of casing 28. The piston is provided with a short stem 39 which is adapted to extend into the upper coil 32 when the piston is in its lower position below the connection of conduit 29 to casing 28. Piston 38 and stem 39 are formed of a suitable non-magnetic material, such as brass, for example. To the lower end of stem 39 is secured a plunger 40 which may be formed of soft iron. The piston 38 is formed with an opening 41 adapted to be closed by a valve 42 which is fixed to the outer end of a leaf-spring 43. The leaf-spring 43 is secured to the top surface of piston 38.

The device 27, vessel 26, and check valve 31 are preferably embedded in the insulation 12 to prevent undesirable evaporation of volatile liquid in these parts by heat transfer from surrounding air. Conduit 30 is also provided with insulation 12 to prevent evaporation of liquid therein.

The coils 32 and 33 are connected to a suitable source of electrical supply by conductors 44 and 45. The energization of the coils is automatically controlled by a thermal relay 46. The relay includes two fixed contacts 47 and 48 which are connected by conductors 49 and 50 to terminals of the coils 32 and 33. The opposite terminals of the coils are connected to conductor 45.

The fixed contact 47 cooperates with a movable contact 51 secured to an end of a bi-metallic strip 52 which is connected to conductor 44. About strip 52 and in thermal exchange relation therewith is provided a conductor 53 to effect quick heating of the strip when contacts 47 and 51 are closed and the electrical circuit for coil 32 is completed. The fixed contact 48 cooperates with a movable contact 54 which is secured to the end of strip 52 and insulated therefrom. The movable contact 54 is connected to conductor 44 by a conductor 55 which is out of thermal exchange relation with the strip 52.

A suitable switch 56 is connected in conductor 44. The switch 56 is only diagrammatically illustrated and may be of any well-known type adapted to be operated by a volatile fluid thermostat. The thermostat is operatively associated with switch 56 and includes a capillary tube 57 and a bulb 58 which is arranged in heat exchange relation with an auxiliary chamber formed by a short vertical tube 59. The tube 59 is closed at its lower end and is connected at its upper end to the upper part of receiver 21. The thermostat is charged with a volatile fluid which increases and decreases in volume with corresponding changes of temperature to effect closing and opening of switch 56.

During operation, vapor formed in evaporator 19 flows through conduit 24 into condenser 16 in which the vapor is condensed. Condensate flows from condenser 16 into vessel 26. Assuming that contacts 48 and 54 are closed so that coil 33 is energized, the plunger 40 is attracted to its lower position so that piston 38 is below the connection of conduit 29 to casing 28. Under these conditions, liquid will flow from vessel 26 through conduit 29 into the upper part of casing 28.

When the bi-metallic strip 52 flexes to close contacts 47 and 51 and open contacts 48 and 54, coil 33 is deenergized and an electrical circuit is completed for coil 32. With coil 32 energized,

plunger 40 is drawn upward into this coil and piston 38 is moved upward in the casing. With upward movement of piston 38, liquid in the upper part of the casing is forced through conduit 30 into the receiver 21 of the evaporator.

After contacts 47 and 51 have been closed, the bi-metallic strip 52 is heated by the current flowing therethrough and also the current flowing in conductor 53 which is disposed about the strip. When bi-metallic strip 52 is heated sufficiently, the strip flexes away from the fixed contact 47 and contact 54 engages contact 48. After coil 32 has been energized for an interval of time, therefore, the bi-metallic strip flexes to open the circuit for this coil and close the circuit for the lower coil 33. When the electrical circuit for coil 33 is completed, plunger 40 and piston 38 are attracted by this coil to their lower positions. During such downward movement and after piston 38 has closed off the lower end of conduit 29, liquid below the piston causes valve 42 to open, thereby permitting liquid below the piston to flow above the piston into the upper part of the casing.

With contacts 48 and 54 closed, no current flows through bi-metallic strip 52 or conductor 53, whereby the strip 52 is permitted to cool. After sufficient cooling strip 52 flexes to open contacts 48 and 54 and close contacts 47 and 51, whereby the electrical circuit for coil 32 is again completed to effect another pumping stroke of piston 38. The check valve 31 is provided to maintain liquid in conduit 30 after each pumping stroke of piston 38, so that the liquid head is not lost when liquid is raised with successive pumping strokes.

When the liquid level in receiver 21 rises so that liquid overflows into the auxiliary chamber formed by the short vertical tube 59, the bulb 58 is cooled. With cooling of bulb 58, the volatile fluid in the thermostat becomes reduced in volume whereby switch 56 is caused to open. When this occurs the device 27 is disconnected from the source of electrical supply and no liquid is returned from condenser 16 to evaporator 19. Subsequently, when the liquid level in the receiver 21 falls below the upper end of tube 59 and the volatile liquid previously introduced therein has evaporated, the temperature of bulb 58 rises. With such rise in temperature of bulb 58, the volatile fluid increases in volume whereby the thermostat becomes effective to close switch 56. This connects device 27 to the source of electrical supply whereby the thermal relay 46 operates in the manner described above to alternately energize coils 32 and 33 to move piston 38 up and down in casing 28 to raise liquid through conduit 30 into evaporator 19.

While a single embodiment of the invention has been shown and described, it will be apparent to those skilled in the art that various modifications and changes may be made without departing from the spirit and scope of the invention, as pointed out in the following claims.

What is claimed is:

1. In a heat transfer system including a closed fluid circuit partly filled with a volatile liquid and having a flooded evaporation portion and a condensation portion below said evaporation portion, an auxiliary chamber communicating with said evaporation portion whereby liquid flows into said auxiliary chamber when liquid reaches a definite level in said evaporation portion, a device for lifting liquid formed in said condensation portion to said evaporation portion

at a higher level, and a control responsive to a temperature condition affected by liquid in said auxiliary chamber for controlling said device.

2. In a heat transfer system including a closed fluid circuit partly filled with a volatile liquid and having a flooded evaporation portion and a condensation portion below said evaporation portion, an auxiliary chamber communicating with said evaporation portion whereby liquid flows into said auxiliary chamber when liquid reaches a definite level in said evaporation portion, a device for lifting liquid formed in said condensation portion to said evaporation portion at a higher level, and a control responsive to

liquid level in said auxiliary chamber for controlling said device.

3. In combination, an enclosure, an evaporator of the flooded type to effect cooling of air in the enclosure, a heat transfer system including said evaporator and a condenser below said evaporator, a device for lifting liquid formed in said condenser to said evaporator at a higher level, and a control for operating said device, said control including a part associated with said evaporator and affected by the liquid level in the latter and also by ambient air temperature in the vicinity of said part.
